UNITED STATES PATENT OFFICE.

WILLIAM HART, OF TROY, NEW YORK, ASSIGNOR OF ONE-HALF TO
LOUIS W. GROAT, OF NEW YORK, N. Y.

KNITTING-NEEDLE.

SPECIFICATION forming part of Letters Patent No. 761,831, dated June 7, 1904.

Application filed August 15, 1903. Serial No. 169,590. (No model.)

To all whom it may concern:

Be it known that I, WILLIAM HART, a citizen of the United States, residing at Troy, in the county of Rensselaer, State of New York, 5 have invented certain new and useful Improvements in Knitting-Needles, of which the following is a description, reference being had therein to the accompanying drawings, in which—

10 Figure 1 is a side elevation; Fig. 2, a similar view showing the beard forced inward to the shank; Fig. 3, a sectional view on the line III III of Fig. 1; Fig. 4, a sectional view taken on the line IV IV of Fig. 1; Fig. 5, a 15 similar view on line V V of Fig. 1; Fig. 6, a similar view on the line VI VI of Fig. 1; Fig. 7, a similar view taken on the line VII VII of Fig. 1; Fig. 8, a sectional view showing the beard forced inward and resting on 20 the needle-shank; and Fig. 9, an elevation of a portion of the needle looking at the beard.

The main object of this invention is to produce a knitting-needle of the spring-hook type in which the beard will be exceedingly strong 25 and in which the point of the beard will be so protected when it is forced inward to the eye of the needle to permit the formed loop to slip off that it will not break or bend outward, as often happens with the needles of this type 30 now in use.

A further object of the invention is to extend the eye—that is, the recess which receives the point of beard—entirely through the shank of the needle, so that any dirt which 35 may lodge therein will be forced out by the point of the beard, thereby keeping the eye clear and unobstructed. By extending the eye entirely through the shank, as hereinafter described, the extreme point of the beard 40 will be out of contact with the bottom thereof when the beard is forced inward, and all danger of breaking or bending outward said point will be avoided.

Referring to the various parts of the needle 45 by numerals, 1 designates the shank, which is cylindrical in cross-section throughout its length. At one of its ends this shank is slightly reduced in diameter and is bent over and back upon itself to form the beard 2

This reduced portion is maintained cylindrical 50 in cross-section to the point 3, slightly beyond the curve part 4. The purpose of this is to maintain the strength of the shank, so that the needle will not be weakened at the point where the beard joins the shank, as is the case in the 55 needles now in use, wherein the shank is flattened and reduced in diameter at the curve part. From the point 3 to the point 5 the beard is flattened, as indicated at 6 in Fig. 5. This portion of the beard is flattened to render it 60 resilient and constitutes the spring portion thereof. This spring portion of the beard is substantially parallel with the shank of the needle when the beard is in its normal position. From the point 5 the beard extends or 65 inclines slightly outward and away from the needle-shank, as at 7 in Fig. 1, and this portion of the beard is concave on its inner side, as shown at 8 in Fig. 6, the purpose of this being to permit this portion of the beard to 70 fit the adjoining cylindrical surface of the needle-shank when the beard is forced inward to close the eye and permit the formed loop to slip off the needle, as shown in Fig. 8. The outer side of the beard is convex, except 75 where the same is flattened to form a spring portion. The point of the beard is cylindrical in cross-section, as shown clearly in Fig. 7, and is adapted to enter the eye or recess 80 10, formed in the needle-shank. This depression or eye is of the same contour as the beard-point, as shown clearly in Figs. 3 and 9, and its bottom is convex to receive the cylindric point of the beard. This eye or recess extends entirely through the needle-shank where 85 the point of the beard extends into it, as shown in Figs. 2 and 7, so that the extreme point is unsupported, and the danger of bending or breaking the said extreme point of the beard will be avoided, the main portion of the 90 point 9 coming in contact with the outward inclined part 11 of the eye, as shown in Fig. 2. This not only prevents the extreme point of the beard being bent back or broken, but also prevents it becoming soiled by contact 95 with dirt or dust in the eye 10.

From the foregoing it will be readily understood that I provide an extremely strong,

durable, and practical knitting-needle. By carrying the cylindrical shank around the curve at the end thereof I avoid the great weakness of the ordinary spring-hook knitting-needle, which is flattened at this point, and is consequently very easily broken. It will also be noticed that by concaving the inner side of the beard at the point where the same will contact with the cylindrical shank 10 of the needle when the beard is forced inward to the shank all danger of breaking or bending at this point and of turning it side-wise is avoided. The concavity in the beard will receive the needle-shank, and the parts 15 will be positively maintained in alinement. By forming the point of the beard cylindrical in cross-section and so forming the eye in the shank that the extreme point of the beard will be out of contact with the needle-shank 20 when the beard is pressed into the eye it will be seen that said eye cannot be turned or broken in ordinary usage.

This needle is well adapted for knitting wire as well as fiber strands, and it is designed 25 not only to provide a strong and durable needle, but one in which the sharp edges or points, which would be liable to injure the fiber, are avoided.

Having thus fully described my invention, 30 what I claim, and desire to secure by Letters Patent, is—

1. A knitting-needle formed with a shank cylindrical in cross-section, a spring-beard connected to said shank by a tapering portion 35 which is cylindrical in cross-section, a portion of said beard being concave on its inward side to receive the cylindrical shank of the needle, and the eye formed in the shank to receive the point of the beard.
2. A knitting-needle formed with a cylindrical shank, a beard connected thereto at one end by a tapering part cylindrical in cross-section, said beard being formed with a flat-

tened spring part, a point portion cylindrical in cross-section, and a portion connecting the 45 spring with the point portion this latter portion being concave on its under side to receive the cylindrical shank of the needle, said shank being formed with an eye to receive the cylindrical point of the needle, said eye at one 50 end extending entirely through the shank and having a convex outward-inclined bottom.

3. A knitting-needle formed with a shank cylindric in cross-section, a spring-beard connected to said shank by a tapering portion 55 which is cylindric in cross-section, a portion of said beard being concave on its inner side to receive the cylindric shank of the needle, an eye formed in this shank to receive the point of the beard, said eye being tapered to 60 correspond with the tapered point of the beard, its bottom being concave to receive the cylindric point of the beard, and its contracted end extending entirely through the shank so that the extreme end of the beard will be within the shank when the beard is forced inward 65 but will be out of contact with the bottom of the eye.

4. A knitting-needle formed with a shank, a spring-beard connected to said shank and 70 formed with a tapered point and an eye formed in the shank to receive the point of the beard, said eye being tapered to receive the correspondingly-tapered point of the beard, the 75 bottom of the eye terminating short of its contracted end whereby when the beard is forced inward its tapered point will lie in the eye of the shank and the extreme end thereof will be out of contact with the bottom of said eye.

In testimony whereof I hereunto affix my 80 signature, in the presence of two witnesses, this 13th day of August, 1903.

WILLIAM HART.
